UNITED STATES PATENT OFFICE.

HENRY L. SCHWARZENBERG, OF CLEVELAND, OHIO.

DESIGN FOR A FISH-SCALER.

SPECIFICATION forming part of Design No. 27,503, dated August 10, 1897.

Application filed June 26, 1897. Serial No. 642,549. Term of patent 3½ years.

To all whom it may concern:

Be it known that I, HENRY L. SCHWARZENBERG, of Cleveland, Cuyahoga county, Ohio, have invented and produced a certain new and useful Design for Fish-Sealers, of which the following is a specification, reference being had to the accompanying drawings, illustrating the design.

In the accompanying drawings, Figure I is a side elevation of the device. Fig. II is a top plan. Fig. III is a transverse section of the ribbed portion of the handle of the device on about line III III, Fig. I.

The fish-scaler comprises, essentially, a flat horizontally-arranged plate A that has its side edges parallel and has the edge at its free end arranged diagonally between the side edges. Plate A at its inner or opposite end terminates in an upwardly-extending handle A', that is curved longitudinally, as shown in Fig. I, and is curved transversely, as shown in Fig. III—that is, the handle of the device is concavo-convex and its upper side is the convex side. The device is stamped from a single piece of metal and the plate A has several rows of teeth *a* struck downwardly from the plate and is thereby provided with a corresponding number of correspondingly arranged rows of vertical holes. The said rows

are arranged parallel with the diagonal outer edge. The diagonal arrangement of the rows of teeth renders all of the teeth visible in a side elevation of the device. In the case illustrated plate A has five rows of teeth. The central row has three teeth arranged equidistant apart. In each of the two rows that are adjacent to opposite sides, respectively, of the central row are four teeth arranged equidistant apart, and in each of the outermost and innermost rows are three teeth that are arranged equidistant apart. Two reinforcing-ribs *a'* *a'* are formed upon the device at the junction of the handle and plate, and said ribs diverge in the direction of the plate. The design consists, essentially, in the flat plate that terminates at one end in a concavo-convex handle, the reinforcing-ribs, and the peculiar arrangement of the rows of teeth.

What I claim is—

The design for a fish-scaler, substantially as herein shown and described.

In testimony whereof I sign this specification, in the presence of two witnesses, this 17th day of June, 1897.

HENRY L. SCHWARZENBERG.
